CLAIM

We claim the ornamental design for a chainsaw, as shown and described.

DESCRIPTION

FIG. 1 is a front perspective view of a chainsaw showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of circled portion 9 of FIG. 1;

FIG. 10 is an enlarged view of circled portion 10 of FIG. 1;

FIG. 11 is an enlarged view of circled portion 11 of FIG. 2; and,

FIG. 12 is an enlarged view of circled portion 12 of FIG. 2. The broken lines depict portions of the chainsaw in which the design is embodied that form no part of the claimed design.
